UNITED STATES PATENT OFFICE.

CHARLES L. SEELEY, OF LA JUNTA, COLORADO,

LOCKING DEVICE.

1,106,521.

Specification of Letters Patent. Patented Aug. 11, 1914.

Application filed March 17, 1911, Serial No. 615,051. Renewed January 18, 1914. Serial No. 811,920.

To all whom it may concern:

Be it known that I, CHARLES L. SEELEY,
a citizen of the United States, residing at
La Junta, in the county of Otero and State
of Colorado, have invented certain new and
useful Improvements in Locking Devices, of
which the following is a specification, ref-
erence being had to the accompanying draw-
ings.

10 This invention relates to improvements in locking devices and more particularly to a device for locking the starting crank of a motor vehicle so that the machine cannot be started in the absence of the owner.

15 The primary object of the present invention is to provide a simple lock which may be easily and quickly operated and comprises a sliding bolt having a bifurcated head for engagement upon opposite sides
20 of the crank, a sliding pin to lock the bolt against movement, and a supplementary lock to prevent retraction of said pin to hold the bolt in its locking position.

Still another object of the invention is to provide a novel form of lock for application to the steering post of a motor vehicle to hold the wheels of the machine in the position to which they have been turned.

Another object of the invention is to provide a device of the above character which may be easily and quickly applied, and may be manufactured at small cost.

With the above and other objects in view, the invention consists of the novel features of construction, combination and arrangement of parts hereinafter fully described and claimed, and illustrated in the accompanying drawings, in which—

Figure 1 is a front elevation of my improved locking device showing the same applied to the starting crank of a motor vehicle; Fig. 2 is a side elevation; Fig. 3 is a section taken on the line 3—3 of Fig. 1; Fig. 4 is a detail perspective view of the locking bar; Fig. 5 is a view similar to Fig. 1 showing the device applied to the steering post of the vehicle and illustrating a slightly modified form of the locking bolt; Fig. 6 is a section taken on the line 6—6 of Fig. 5.

50 Referring in detail to the drawings 5 designates a plate which is suitably secured upon a suitable base plate having flanges 6 upon its edges, said plate being secured to the dash-board D of the vehicle. The surface of the plate 5 is provided with a central longitudinal channel or groove 7 which, at

one end of the plate is enlarged as indicated at 8, the end flange 6 of the base plate being cut away as shown at 9.

The locking bar 10 is mounted upon the base plate 5 and is longitudinally movable in the groove 7 thereof. This bar is provided with a bifurcated head 11 on one end and is also formed with a longitudinally projecting pin 12 which is centrally disposed between the arms of the bifurcated head. The shank of the locking bar has an opening 13 therein to receive a catch 14 which is transversely movable in the base plate 5. This plate is provided with a transverse cylindrical channel 15 in which the catch 14 moves. The channel 15 opens into the longitudinal groove 7 and also extends into the opposite wall of the groove for a slight distance as indicated at 15' to receive the end of the catch 14 after it has passed through the opening 13 in the locking bar 10. A lock 16 of any desired type is also mounted in the plate 5 and is adapted to be actuated to prevent retraction of the catch 14 after the same has been moved to its locking position in the bar 10.

The starting crank C is provided with an opening c to receive the centrally projecting pin 12 on the end of the locking bolt 10, and said crank at opposite sides is flattened as indicated at c' to receive the parallel arms of the bifurcated head 11. When the bolt 10 is in locking position as shown in Fig. 1, it will be obvious that any turning movement of the crank is rendered impossible, and as the catch 14 is held against retraction by means of the bolt of the lock 16, the machine cannot be started by anyone during the absence of the owner thus obviating the liability of its theft. 95

It is well known that the starting cranks of automobiles are automatically pushed forward to an inoperative position by a spring and that they must be pushed rearwardly so as to effect a clutching engagement with the crank shaft of the motor, before the latter can be turned so as to impart an initial impulse to the engine. By providing the pin 12 and forming the starting crank with an aperture extending transversely thereof and through which the pin projects in the locking position of the bar 10, it is evident that the starting crank C cannot be pushed rearwardly so as to bring about this clutch connection, whereas if the pin 12 were not employed and the recessed

sides of the starting crank and the forked arms of the bar 10 depended upon alone to hold the crank in an inoperative position, it would be possible to move the starting 5 crank rearwardly and effect the clutching engagement of the crank and the crank shaft so that a subsequent attempt to turn the crank might be inadvertently made which would tend to wear the parts of the 10 locking device and which might result successfully in straining the parts to such an extent as to permit the motor to be started. By providing the pin 12, all liability to injure the parts, as above pointed out, will be 15 precluded.

In Fig. 5 I have illustrated the application of my locking device to the steering post P of a motor vehicle. In this form, the central pin 12' formed on the head of the 20 locking bolt is preferably shorter than the pin 12 previously described so that it enters through openings p in the casing P' of the post P, said post and casing being tubular in form. The outer casing P' is 25 also provided with flattened surfaces p' at opposite points to receive the arms of the bifurcated head of the locking bolt. The bolt is locked in a similar manner to the previously described form of the device. 30 The locking bolt 10 is preferably of cylindrical form, though it will of course be obvious that if desired this bolt may be rectangular in cross section.

From the foregoing it is thought that the 35 construction and operation of my improved locking device will be readily understood, without necessitating a more extended explanation. The device can also be easily applied to other parts of the vehicle construction such as the axle or hub, without 40

departing from the features of construction embodied therein. It will further be obvious that the lock can be manufactured at an extremely low cost, is capable of easy and quick application and effectually operates to prevent the actuation of the propelling mechanism during the absence of the 45 owner.

While I have shown and described the preferred construction and arrangement of the various parts, it will be understood that the device is susceptible of considerable modification without departing from the essential feature or sacrificing any of the advantages thereof. 50

Having thus described the invention what is claimed is:—

A device of the class described, comprising a casing having a longitudinal guide slot having an enlarged U-shaped upper end, a locking bolt adapted for movement in the longitudinal guide slot and having an enlarged head portion adapted for engagement within the upper enlarged U-shaped end of the guide slot when the locking bolt is in its 55 lowermost position, said head being adapted for engagement around a crank shaft and having a prong for engagement in the crank shaft to lock the latter against rotation and reciprocation when the locking bolt is in the 60 extended position, and means carried by the casing for securing the locking bolt in either position.

In testimony whereof I hereunto affix my signature in the presence of two witnesses. 75

CHARLES L. SEELEY.
